(57) **CLAIM**

The ornamental design for an auxiliary sheet feeder for an inkjet printing mechanism, substantially as shown and described.

DESCRIPTION

FIG. 1 is a perspective view of an auxiliary sheet feeder for an inkjet printing mechanism, in accordance with the present invention;

FIG. 2 is a top plan view thereof;

FIG. 3 is a front elevational view thereof;

FIG. 4 is a rear elevational view thereof;

FIG. 5 is a left side elevational view thereof; and,

FIG. 6 is a right side elevational view thereof.

The broken line showing of potential mechanical interconnections where the auxiliary sheet feeder may be coupled to the inkjet printing mechanism in FIGS. 1-6, is for illustrative purposes only, and forms no part of the claimed design. The bottom view has been omitted because it forms no part of the claimed design.
